UNITED STATES PATENT OFFICE.

HORACE Z. NABERS, OF COLUMBIA, SOUTH CAROLINA.

VENTILATING TRANSOM.

1,403,054.

Specification of Letters Patent. Patented Jan. 10, 1922.

Application filed November 11, 1919. Serial No. 337,287.

To all whom it may concern:

Be it known that I, HORACE Z. NABERS, a citizen of the United States, residing at Columbia, in the county of Richland and

5 State of South Carolina, have invented certain new and useful Improvements in Ventilating Transoms, of which the following is a specification.

10 This invention relates to ventilating transoms and the object thereof is to provide such a transom with a plurality of louvers mounted to turn on their axes and an actuating bar carried by said axes and adapted to open and close the louvers at the will of 15 the operator, means being provided to hold said bar in adjusted position.

Another object is to provide a slatted transom constructed to be burglar proof and yet thoroughly ventilate the room in connection with which it is used and which eliminates pivots and transom lifts.

20 With the foregoing and other objects in view, which will appear as the description proceeds, the invention resides in the combination and arrangement of parts and in the details of construction hereinafter described and claimed, it being understood that changes in the precise embodiment of the 25 invention herein disclosed may be made 30 within the scope of what is claimed without departing from the spirit of the invention.

In the accompanying drawings:

35 Figure 1 represents a front elevation, taken from the interior of the building, of a transom constructed in accordance with this invention.

40 Fig. 2 is a transverse vertical section thereof taken on the line 2—2 of Fig. 1.

45 Fig. 3 is a similar view taken on the line 3—3 of Fig. 1.

Fig. 4 is a detail perspective view of one 50 end of one of the louvers with the rod which forms its axis connected therewith and broken off.

Fig. 5 is a similar view of a portion of the actuating bar.

55 In the embodiment illustrated the transom constituting this invention is shown in the form of a sash or frame F fixed stationary in an opening in the side wall S of a building. Mounted in the frame F is a plurality of louvers 1 preferably constructed of glass and each shown with a metal cap 2 on each end thereof. These caps 2 are each

provided on one face thereof with a laterally extended boss 3 apertured from end to end longitudinally of the louver to receive a rod 4 which forms the axis of the louver. As 60 stated above, each louver has a cap 2 on each end and the rod 4 extends through the apertures in the bosses on these caps and is fixedly connected therewith by set screws 5, although obviously these rods may be otherwise secured to the louvers if found desirable. 65

The rods 4 extend longitudinally of the sash or frame F and are provided at their opposite ends with cranks 6, the terminals 70 of which are pivotally mounted in bearings 8 on the outer face of the frame F at its opposite ends. Any desired numbers of louvers 1 may be mounted in the transom frame, six being here shown, three being arranged at one end of the transom and three at the other end and separated by a partition strip F¹ across which the rods 4 extend as is shown clearly in Fig. 1. 75

An actuating bar 7 is shown positioned 80 at each end of the transom extending transversely thereof and through apertures 9 of which extend the crank ends 6 of the rods 4. One of these bars 7 is provided on its inner face with a laterally extending arm 10 having an eye 11 at its free end with which is designed to be engaged an operating rod 12 for moving the bar with which it is connected longitudinally thereby rock- 90

ing the rods 4 and opening or closing the louvers according to the direction in which the operating member is moved. While two bars 7 are shown, one only may be used. Between each of the bars 7 and the frame F 95 are outwardly bowed spring metal strips 13 secured to the bars, two being here shown for each bar with their bowed portions positioned to engage the end members of the frame F for frictionally holding the bars 100 in adjusted positions. It will thus be seen that these springs also operate through the bars to hold the louvers in adjusted position. While these springs 13 are shown located as above described, they may be otherwise 105 mounted if desired provided they effect the holding of the louvers in adjusted position.

From the above description it will be seen that the louvers or slats 1 may be readily connected with or disconnected from their 110 respective rods or axes by loosening the set screws 5, straightening out one of the crank

ends and slipping off the louver from the rod which may be replaced by another in case of breakage.

With the parts in the position shown it will be seen that the crank ends 6 of the rods 4 are arranged at an angle of about 60° to the vertical which is the position assumed when the slats or louvers are closed and that they may be opened by a pull on the operating rod 12 and closed by an upward push thereon. It is, of course, to be understood that the slats while shown as made of glass may be of any desired material, glass being preferable to permit the entrance of light.

From the foregoing description taken in connection with the accompanying drawings the advantages of the construction and the method of operation will be readily apparent to those skilled in the art to which the invention appertains, and while I have described the principle of operation of the invention together with the device which I now consider to be the best embodiment thereof I desire to have it understood that the showing is merely illustrative and that such changes may be made as are within the scope of the claimed invention.

Having thus fully described my invention what I claim as new and desire to secure by Letters Patent is:

1. A transom or the like composed of a frame having a rod arranged longitudinally thereof and provided with crank ends mounted to turn on the ends of said frame, a louver carried by said rod, and an actuating bar mounted to move transversely of said frame and through which one of said crank ends extends.
2. A transom or the like composed of a frame having a rod arranged longitudinally thereof and provided with crank ends

mounted to turn on the ends of said frame, a louver carried by said rod, an actuating bar mounted to move transversely of said frame and through which one of said crank ends extends, an arm extending laterally from said bar, and means connected with said arm to operate said bar.

3. A transom or the like composed of a frame having a rod arranged longitudinally thereof and provided with crank ends mounted to turn on the ends of said frame, a louver having metal caps on its opposite ends with apertured lugs projecting from one face thereof, said rod extending through said lugs, set screws securing the rod to the caps, an actuating bar mounted to move transversely of said frame and through which one of said crank ends extends, means for reciprocating said bar to rock said crank rod and an outwardly bowed plate spring carried by said bar and adapted to frictionally engage said frame to hold said bar and louver in adjusted position.

4. A transom or the like composed of a frame adapted to be fixedly mounted in an opening, a plurality of rods arranged longitudinally of said frame and having crank ends pivotally connected with the ends of said frame, louvers carried by said rods to turn therewith, an actuating bar arranged transversely at one end of said louvers and through which the crank ends of the rods extend, an arm projecting laterally from said bar, and an operating element connected therewith.

In testimony whereof I have affixed my signature in presence of two witnesses.

HORACE Z. NABERS.
